CLAIM

The ornamental design for an electrical current sensor, as shown and described.

DESCRIPTION

FIG. 1 is a front view of the electrical current sensor;
FIG. 2 is a bottom view of the electrical current sensor;
FIG. 3 is a left side elevation view of the electrical current sensor, the right side elevation view being a mirror image; and,
FIG. 4 is a perspective view of the electrical current sensor.
The rear view is not shown as same does not form any part of the claimed design.
